UNITED STATES PATENT OFFICE

OTTO A. PETERSON, OF STOUGHTON, MASSACHUSETTS, ASSIGNOR TO GEORGE E. BELCHER COMPANY, OF STOUGHTON, MASSACHUSETTS, A CORPORATION OF MASSACHUSETTS

LAST

Application filed September 18, 1923. Serial No. 663,468.

My present invention relates to certain further improvements in divided lasts and particularly in such as have a snap or tendency to stay set in either their open or closed position. This has been accomplished generally in two manners, i. e. by the overriding of an intermediate resisting of wedging surface or by the shifting of lines of force relative to an actual or an imaginary center of rotation as in my own prior Patent No. 1,195,266 which involved however certain other principles of construction important in this art.

My present invention contemplates a combinational relation in which the obstructive or resisting surface principle is combined with my own principle of elastic linkage whereby the advantages of the former are preserved while avoiding the obvious impossibilities of mechanical compression of the wood itself. I further contemplate certain advantageous combinations in the knuckle curvature by which I am able to accomplish a maximum of efficiency with a simplicity of structure which makes manufacturing on a commercial basis possible.

As illustrative of the principles of my invention I have shown in the accompanying drawings two forms of the many. These are to be considered largely as illustrative but are both capable of manufacture as commercial factory lasts. Throughout specification and drawings like reference characters are employed to indicate corresponding parts, and in the drawings:

Fig. 1 is a side elevation of a last in accordance with my invention.

Fig. 2 is a sectional view of the same in extended position.

Fig. 3 a similar view in broken position.

Fig. 4 an enlarged diagrammatic view showing the knuckle curvatures.

Fig. 5 a central vertical section through another form of my last in extended position, and

Fig. 6 a similar view in broken position.

It will be seen that my last comprises a fore part 1 and heel part 2 of usual type having an intermediate knuckle joint or bearing which will be discussed further

later, the said parts being kept together and the bearing maintained by a U-shaped link 3 pivoted at one end in the fore part 1 at the knuckle center 4 and at its rear as at 5 in the heel part.

This U-shaped link as set forth in my prior patent is of flat stock and has a slight resiliency. Working in the narrow slots 1¹ and 2¹ it affords a steady bearing and takes up lateral strains while constantly holding the two parts snugly together.

The knuckle joint as will be seen by reference to Fig. 4 comprises two portions 6 and 7. The portion 6 is struck on a true radius from the pivot center 4 and terminates in a horizontal shoulder 8. The joint is continued below this shoulder in a sinuous or undulating surface, the upper portion 7¹ being formed as a projecting cam surface, and the lower portion 7² being reversely concaved. This leaves the face of the heel part with a portion 2² conforming to the portion 7² which in the breaking of the last rides up over the portion 7¹ until it assumes the position shown in Fig. 3 in which it has overridden the edge of the shoulder 8. As appears in Fig. 2, the shoulder 8 constitutes a stop and being horizontally disposed it has no resistive action to the longitudinal tendency of the spring to pull the parts together but combined with the interlocking action of the faces 7² and 2² it has a very strong holding action in steadyng the last during the leveling up of the shoe.

This form of joint therefore provides for the two positions of the last parts and their retention by a snapping action of the last without any wearing of the resisting or wedging surfaces of the knuckle inasmuch as the link 3 yields to permit the passage of the parts.

While this form of joint has many advantages the shoulder 8 may in some cases be omitted as appears in Figs. 5 and 6. In these figures the knuckle portion 6^a is a cylindric on the fore part 1 struck on the pivot 4 of the forward end of the link as a central axis but merges at the point 7^a into a reversed curvature which leaves a cam shaped portion 2^a on the heel part which

must ride over the surface 6^a when passing the point 7^a. In so doing the link 3 yields as before to permit the camming action of these parts.

Such lasts are not only convenient to make and to operate but are long lived and convenient to manufacture. The positioning of the pivot pin 4 in the central axis of the knuckle facilitates and simplifies the sawing of the knuckle joint in dividing the last and gives the pivot pin 4 an advantageous position both as a central axis of rotation of the heel part on the fore part and as regards the opposite pin 5 of the link and the line of force resultant from the resiliency of the link which is directed between them. It will be seen that in each position of the link this line of force is directed from the heel part directly towards the pin 4 as a center of rotation and although the link stretches slightly during the passing of those portions of the knuckle surface which have a camming action, its tendency is in both broken and extended position to hold the last in the position desired.

Various modifications in the construction and operation of my device may obviously be resorted to all without departing from the spirit of my invention if within the limits of the appended claims.

What I therefore claim and desire to secure by Letters Patent is:—

1. A divided last comprising a fore part and a heel part having intermediate cooperating bearing surfaces, a resilient connecting link connected at one end in the fore part and at the other end in the heel part to press said bearing surfaces together, said surfaces having engaging portions including an eccentric and a concentric portion subjected to the pressure exerted by said resilient link whereby to maintain the last parts in yielding engagement, and to be yieldingly resistant to movement from the extended position by reason of the eccentric position.

2. A divided last comprising a fore part and a heel part having intermediate cooperating bearing surfaces, said surfaces including a concentric and an eccentric portion, a resilient connecting link connected at one end in the fore part and at the other end in the heel part to normally yieldingly press said bearing surfaces together, said surfaces having the eccentric engaging surfaces disposed below the line of pressure exerted by said resilient link whereby to maintain the last parts in engagement so as to be yieldingly resistant to movement from extended position.

3. A divided last comprising a forepart and a heel part having intermediate cooperating bearing surfaces, said surfaces including concentric and eccentric portions, a yielding connecting member connected at one end in the forepart and at the other end in

the heel part to normally exert a yielding stress between said bearing surfaces, the eccentric portions of said bearing surfaces cooperating with the yielding connecting member and serving to maintain the last parts in yieldingly interlocked engagement when in either extended or broken position. 70

4. A divided last comprising a forepart and a heel part having intermediate cooperating bearing surfaces each of said surfaces including a concentric and eccentric portion, a resilient connecting member having one end pivotally connected at the center of the concentric portion, the other end of the yielding member being connected in the second part of the last so as to normally exert a yielding pressure between the cooperating bearing surfaces, a line passing through the points of connection at the ends of the resilient connecting member passing through the radial center of the concentric portion when the last is in either an extended or broken position, the eccentric portions of the bearing surfaces on each of the respective last parts, cooperating with the yielding connecting member to maintain the last parts in yieldingly interlocked engagement when in either extended or broken position. 85

In testimony whereof I affix my signature.
